FASTENING MACHINE

Chester B. Thayer, Benton Harbor, Mich.; Pearl
C. Thayer administratrix of said Chester B.
Thayer, deceased

Application April 22, 1935, Serial No. 17,659

10 Claims. (Cl. 1—50)

This instant invention relates to fastening machines and more particularly to devices for stapling basket bottoms to the side walls.

The primary objects of the present invention 5 are to provide a machine of the character above indicated which is particularly adapted for use in stapling pre-formed basket bottoms to the side walls of tub type baskets; to provide such a device which is simple in construction; to provide such 10 a device which is effective and convenient in use; and, to provide such a device which is economical in manufacture.

An illustrative embodiment of the invention is shown in the accompanying drawings, wherein:

15 Figure 1 is a bottom plan view of a tub type basket whose pre-formed bottom has had one of its pre-started staples pierced through its peripheral hoop and into clinching engagement with the bottom hoop of the basket by the device of the 20 instant invention and in the manner illustrated in Figure 6;

Figure 2 is a side elevational view thereof, the basket being tipped upside down;

25 Figure 3 is a sectional view of the pre-formed basket bottom on line 3—3 of Figure 1, the stapling machine being omitted from the view;

Figure 4 is an enlarged fragmentary top plan view of the stapling device, here shown as placed in position relative to the basket and its bottom 30 prior to the stapling operation;

Figure 5 is a fragmentary side elevational sectional view thereof on line 5—5 of Figure 4; and

35 Figure 6 is an enlarged sectional view on line 6—6 of Figure 5, but showing the position of the parts at the end of the stapling operation.

Referring to the drawings in which like parts of the device, basket and its pre-formed bottom therein shown are designated by the same numerals in the several views, a tub type basket having a side wall formed by a plurality of staves 10 secured together in circular form by a bottom hoop 11, middle hoop 12 and top hoop 13 as by staples 14, is provided with a pre-formed bottom formed by the cross members 15 secured together 40 by a hoop 16. The hoop 16 is preferably, though not necessarily, provided with a plurality of pre-started spaced fasteners such as the staple fasteners 17 which are consecutively caused to pierce the hoop 16, staves 10 and into clinching engagement with the bottom hoop 11 by the stapling machine of the instant invention and in the manner best shown in Figure 6 and as hereinafter presently described.

The stapling device comprises the member 18, 55 here shown as a triangularly formed bifurcated plate, whose slot 19 is provided with a transverse pin 20 slidable therein. The closed end of this bifurcated plate is provided with a transversely disposed angle iron member 21 which is secured 60 thereto by a bolt forming a plunger 22 disposed

in parallelism with and below the slot 19 as by the nut 23 and the collar 24.

The free end of the plunger, adapted to act as a hammer, is here shown as having a sleeve 25 in sliding embrace thereon, the outer end of the sleeve being provided with a slotted end 26 for engaging the head of a staple fastener 17. Means for limiting the sliding movement of the sleeve relative to the plunger comprises the set screw 27 passing through the wall of the sleeve and into the elongated longitudinally milled slot 28 in the plunger as best shown in Figure 6 and a coiled expansion spring 29 encircling the plunger and interposed between the collar 24 and the inner end of the sleeve normally urges the sleeve outwardly as best shown in Figure 5.

A pair of arms 30, normally disposed at an angle to each other on opposite sides of the pin 20 and as best shown in Figure 4, are pivotally connected with the pin. The inner ends of these 20 arms are each provided with a depending portion forming an anvil 31 for the purpose hereinafter explained and each arm is provided with an offset portion or ear 32.

A pair of links 33, each pivotally connected at 25 one end to the angle iron member 21 as by bolts 34 and on opposite sides of the plate 18 are likewise each pivotally connected to an ear 32 as by bolts 35.

In operation, the device is placed on the bottom surface of the pre-formed basket bottom with its arms 30 in spread apart relation and with the anvils 31 along the outer marginal edge of the bottom hoop 11 and with the slotted end 26 of the sleeve 25 in radial aligning engagement with a staple fastener 17, all as best shown in Figures 5 and 6. The arms 30 are then manually folded toward each other as indicated by the arrows in Figure 4 to closed position shown in Figure 1.

As the arms 30 are thus folded toward closed 40 position, the links 33 cause the plunger 22 to move outwardly and relatively to its sleeve 25 and when the shank of the set screw 27 engages the outer end of the milled slot 28, the sleeve 25 is likewise caused to move outwardly and the 45 plunger drives the staple through the hoop 16, a stave 10 and the outer hoop 11 and clinches the staple against the anvils 31 as best shown in Figure 6, in which action the sleeve may be forced backwardly against the pressure of spring 29. 50 The sleeve exerts some driving action on the staple in the outward movement of the plunger such action being however yielding in character by reason of said spring. The arms 30 may then be spread outwardly from their position shown 55 in Figure 1 and as indicated by the arrows for the next stapling operation.

The sleeve 25, may if desired, be provided with a deeper slot 26 than is shown in the drawings 60 in which a staple may be manually placed in in-

stances where the staples 17 are not pre-started in the hoop 16.

It will thus be seen that the machine of the instant invention is particularly well adapted for 5 use in stapling a pre-formed basket bottom to the side wall of a tub type basket and that the device is simple in construction, effective and efficient in use, and is economical in manufacture.

While but one specific embodiment on the invention has been herein shown and described, it 10 will be understood that numerous details of the construction shown may be altered or omitted without departing from the spirit of this invention as defined by the following claims.

15 I claim:

1. In a device of the class described, a member having a slot therein, a hammer plunger member disposed in parallelism with the slotted member and in rigid association therewith, a pin within 20 said slot and slideable therein, a pair of arms disposed on opposite sides of the pin, having anvil portions and pivotally connected with said slotted member, and a pair of links each pivotally connected at one end to said slotted member on an 25 opposite side thereof and each pivotally connected at its other end to an anvil arm.

2. In a device of the class described, a member having a slot therein, a hammer plunger member disposed in parallelism with the slotted member 30 and in rigid association therewith, a hammer sleeve slidably embracing the plunger, a pin within said slot and slideable therein, a pair of anvil arms disposed on opposite sides of the pin and 35 pivotally connected therewith, and a pair of links each pivotally connected at one end to said slotted member on an opposite side thereof and each pivotally connected at its other end to an anvil arm.

3. In a device of the class described, a member 40 having a slot therein, a hammer plunger member disposed in parallelism with the slotted member and in rigid association therewith, a hammer sleeve limitedly slidably embracing the plunger, a pin within said slot and slideable therein, a pair 45 of anvil arms disposed on opposite sides of the pin and pivotally connected therewith, and a pair of links each pivotally connected at one end to said slotted member on an opposite side thereof and each pivotally connected at its other end to 50 an anvil arm.

4. In a device of the class described, a member having a slot therein, a hammer plunger member disposed in parallelism with the slotted member and in rigid association therewith, a hammer 55 sleeve limitedly slidably embracing the plunger, an expansion spring interposed between the plunger and sleeve, a pin within said slot and slideable therein, a pair of anvil arms disposed on opposite sides of the pin and pivotally connected 60 therewith, and a pair of links each pivotally connected at one end to said slotted member on an opposite side thereof and each pivotally connected at its other end to an anvil arm.

5. In a device of the class described, a member 65 having a slot therein, a hammer plunger member disposed in parallelism with the slotted member and in rigid association therewith, a sleeve slideably embracing the plunger and provided with a hammer end for engaging the end of a fastener, a pin within said slot and slideable therein, a pair 70 of anvil arms disposed on opposite sides of the pin and pivotally connected therewith, and a pair of links each pivotally connected at one end to said slotted member on an opposite side thereof and each pivotally connected at its other end to an anvil arm.

to said slotted member on an opposite side thereof and each pivotally connected at its other end to an anvil arm.

6. In a device of the class described, a member 5 having a slot therein, a hammer plunger member disposed in parallelism with the slotted member and in rigid association therewith, a sleeve slidably embracing the plunger and provided with a slotted end for engaging the head of a staple fastener, a pin within said slot and slideable therein, a pair of anvil arms disposed on opposite sides of the pin and pivotally connected therewith, and a pair of links each pivotally connected at one end to said slotted member on an opposite side thereof and each pivotally connected 10 at its other end to an anvil arm.

7. In a device of the class described, a member having a slot therein, a hammer plunger member disposed in parallelism with the slotted member and in rigid association therewith, a sleeve limitedly slidably embracing the plunger and provided with a hammer end for engaging the end of a fastener, a pin within said slot and slideable therein, a pair of anvil arms disposed on opposite sides of the pin and pivotally connected therewith, 25 and a pair of links each pivotally connected at one end to said slotted member on an opposite side thereof and each pivotally connected at its other end to an anvil arm.

8. In a device of the class described, a member 30 having a slot therein, a hammer plunger member disposed in parallelism with the slotted member and in rigid association therewith, a sleeve limitedly slidably embracing the plunger and provided with a slotted end for engaging the head of a staple fastener, a pin within said slot and slideable therein, a pair of anvil arms disposed on opposite sides of the pin and pivotally connected therewith, 35 and a pair of links each pivotally connected at one end to said slotted member on an opposite side thereof and each pivotally connected at its other end to an anvil arm.

9. In a device of the class described, a member having a slot therein, a hammer plunger member disposed in parallelism with the slotted member 45 and in rigid association therewith, a sleeve limitedly slidably embracing the plunger provided with a hammer end for engaging the end of a fastener, an expansion spring interposed between the plunger and sleeve, a pin within said slot and slideable therein, a pair of anvil arms disposed on opposite sides of the pin and pivotally connected therewith, and a pair of links each pivotally connected at one end to said slotted member on an opposite side thereof and each pivotally connected at its other end to 50 an anvil arm.

10. In a device of the class described, a member having a slot therein, a hammer plunger member disposed in parallelism with the slotted member and in rigid association therewith, a sleeve limitedly slidably embracing the plunger and provided with a slotted end for engaging the head of a staple fastener, an expansion spring interposed between the plunger and sleeve, a pin within said slot and slideable therein, a pair of 60 anvil arms disposed on opposite sides of the pin and pivotally connected therewith, and a pair of links each pivotally connected at one end to said slotted member on an opposite side thereof and each pivotally connected at its other end to 65 an anvil arm.

CHESTER B. THAYER.
